CLAIM

(22) Filed: **Sep. 2, 2003**

The ornamental design for a surface configuration of a front bumper for a vehicle, as shown and described.

(30) **Foreign Application Priority Data**

DESCRIPTION

Mar. 3, 2003 (DE) 403 01 889

This application is related to the following co-pending application, of the inventor, filed on even date herewith: Application Serial No. 29/189,171, entitled "Surface Configuration of a Vehicle, Toy and/or Other Replicas".

(51) **LOC (7) Cl.** **12-16**

FIG. 1 is a left, perspective view of a surface configuration of a front bumper for a vehicle according to my novel design, the right, perspective view being mirror symmetrical;

(52) **U.S. Cl.** **D12/169**

FIG. 2 is a front view of the surface configuration of a front bumper for a vehicle according to my novel design; and, FIG. 3 is a left side view of the surface configuration of a front bumper for a vehicle according to my novel design, the right side view being mirror symmetrical.

(58) **Field of Search** D12/169, 196, D12/190, 181; 296/180.1, 180.2; 293/102, 113, 115, 120

The broken lines are for illustrative purposes only and form no part of the claimed design.
